(57) **CLAIM**

The ornamental design for a bite stick, as shown and described.

DESCRIPTION

FIG. 1 is a perspective view of a bite stick showing my new design;

FIG. 2 is a bottom elevation view thereof;

FIG. 3 is a top elevation view thereof;

FIG. 4 is a left edge view thereof;

FIG. 5 is a right edge view thereof;

FIG. 6 is a front edge view thereof; and,

FIG. 7 is a rear edge view thereof.

The broken line showing in the FIGS. 1 through 5 are for illustrative purposes only and forms no part of the claimed design.
